LOUIS H. PALL, OF CINCINNATI, OHIO

FABRIC-SAMPLE BINDER AND METHOD OF FOLDING SAID SAMPLES

Application filed October 10, 1927. Serial No. 225,218.

The invention relates particularly to salesmen's fabric samples and binders to retain the said samples in folded position.

Heretofore, it has been customary for tailoring firms to supply their salesmen with fabric or cloth samples cut in pieces measuring approximately forty-eight inches in length and twenty-seven inches in width. Each sample is folded from end to end with approximately nine inches of the width of the material upon itself, then the fabric is folded from end to end with approximately eight inches of the width of the material, from the side opposite the side just previously folded, upon itself with the latter fold overlapping the first mentioned fold, whereby the total width of the sample thus folded is approximately ten inches. Then the sample is folded upon itself end to end with the edge of the last mentioned fold positioned inwardly. Then a paper-pulp or fiber binder or tag, having the identification number and address of the tailoring firm and any other data printed thereon, and of dimensions approximately ten inches in length and four inches in width, is folded with its side edges in alignment and the aligned ends of the sample are inserted between the folds of the binder which is permanently secured to the fabric as by stitching, rivets, or other suitable methods of fastening. The dimensions of the binder and sample when completely folded is approximately ten inches x twenty-four inches.

It is, therefore, quite apparent that while the dimensions of the unfolded fabric sample is twenty-seven inches x forty-eight inches the area of one side of the folded sample is actually not more than ten inches x twenty-two inches. Moreover, since the binder is permanently fixed to the aligned end edges of the sample, which is folded with its side edges between the outer layers of the sample, it is impractical for a prospective purchaser to unfold the fabric, but to increase the area of the sample for inspection the hands are inconveniently inserted between the folds and the side edges of the cloth are pulled outwardly. The natural desire of an inspector of the folded fabric sample is to increase the available area for close inspection and the natural inclination of such person is to insert his hand between the folds and attempt to spread the sample before his gaze. In doing so the inwardly folded portion of the sample is disarranged and consequently, since this portion not always is smoothed and properly rearranged before the salesman tightly packs the samples in his trunk, or other container, the outer layers, as well as the inner layers, of the fabric soon become creased and wrinkled and, therefore, the sample is unattractive and is not in proper and neat condition for later presentation by the salesman to prospective buyers for inspection. The result of folding fabric samples in this manner and securing the end edges in the binder, therefore, is that prospective purchasers of the material are not favorably impressed with the quality of the fabric and beauty of its pattern, whereby the volume of the salesman's business is materially decreased. Moreover, after a certain period of use the samples must be replaced with new ones, or, at considerable expense and inconvenience, the binders are removed and the creases and wrinkles are pressed from the fabric after which operations the material is refolded and remounted in the binders.

Therefore, the object of the invention is to provide a simple, economical and efficient binder or tag adapted to be secured to the aligned ends of a piece of fabric after said piece is folded end to end, after which said piece is adapted to be folded twice upon itself and the ends of said piece are releasably retained in the last mentioned folded position, whereby a prospective purchaser may quickly and conveniently partly unfold the fabric and thereby increase the area of the sample for inspection, and after the inspection is completed said fabric may be quickly and conveniently folded to the usual size of such samples and releasably secured in its folded position.

Other objects will be apparent from reference to the hereinafter description.

The invention consists in the combination and arrangement of the various parts and elements, in the details of the construction, and in the method of folding the samples, as set forth and claimed.

In the drawings:

Fig. 1 is an inside elevational view of the binder;

Fig. 2 is a bottom view of the same;

Fig. 3 is a section taken on a line corresponding to line 3—3 in Fig. 1;

Fig. 4 is an inside elevational view of the binder with the fabric piece fixed thereto;

Fig. 5 is an inside elevational view of the binder and fabric partly folded;

Fig. 6 is a side plan view of the binder and sample fabric completely folded;

Fig. 7 is a section taken on a line corresponding to line 7—7 in Fig. 4, with parts broken away;

Fig. 8 is a plan view of the unfolded fabric piece;

Fig. 9 is a longitudinal sectional section of a fastener.

In the preferred construction of the invention I provide the pliable rectangular binder or tag 1 formed from leather, imitation leather, fiber, or other suitable material. The binder is folded upon itself from its end 2 to its end 3 with the lower longitudinal edges 4 and 5, of the inner and outer sides 6 and 7, in alignment. The dimensions of the binder in this instance is twenty-seven x two inches when folded.

Secured to the binder adjacent its upper longitudinal edge 8 are the fasteners 9 and 10. The fasteners may be of any usual type adaptable for the purposes intended, but are here shown in the form of "snaps" of usual construction having a resilient tongue adapted to be "snapped" or forced into a recess and such as are used to releasably fasten gloves, curtains and the like. The fasteners 9 and 10 comprise the male and female members 11 and 12, and 13 and 14, each having the flanges 15 and 16, respectively, between which the sides 6 and 7 of the binder are secured. The female members 12 and 14, respectively, of the fasteners 9 and 10 are positioned adjacently the ends 2 and 3 of the binder and have in their sides 17 the recesses 18 and 19 for receiving the tongues 20 and 21 of the respective male members 11 and 13 which are positioned between the female members. The recessed sides 17 of both the female members are adjacent the inner side 6 of the binder, whereas the tongues 20 and 21 of the male members extend outwardly of the inner and outer sides 6 and 7 respectively of the binder, for purposes hereinafter fully explained. The fasteners are spaced in accordance with the desired dimensions of the completely folded sample.

The rectangular fabric piece 22 may be of suitable dimensions, but preferably measures twenty-seven inches x forty-eight inches. First, it is folded upon itself with its end 23 to its end 24 and with these ends aligned. Then the ends 23 and 24 are inserted between the sides 6 and 7 of the binder 1 and are suit-

ably secured permanently thereto as by the stitches 25, whereby the sample, as shown in Fig. 2, of double thickness of material is formed having dimensions of approximately twenty-seven inches x twenty-four inches and capable of being thoroughly examined by prospective purchasers.

When, however, it is desirable to fold the sample to conform with the usual dimensions of salesman's fabric samples the material and binder is folded in the position shown in Fig. 5, with its side edge 26 positioned approximately eight inches from the edge 27 and the tongue 21 of the male member 13 of the fastener 10 is "snapped" into the recess 19 of the female member 14, then the sample and binder is folded with its edge 27 approximately one inch from the folded edge 28 as shown in Fig. 6, and the tongue 20 of the male member 11, of the fastener 9, is "snapped" into the recess 18 of the female member 12, whereby the size of the completely folded sample and binder is approximately ten inches x twenty-four inches, or the same, or approximately the same, as the dimensions of the usual salesman's fabric sample. However, when the sample, in its completely folded form shown in Fig. 6, is submitted to a prospective purchaser for inspection, if the latter desires to thoroughly examine the material, he may conveniently separate the male members from the female members of the fasteners 9 and 10, and the sample may be unfolded to the form shown in Fig. 2, whereby the area of the fabric available for close examination is considerably increased.

Since the dimensions of the unfolded sample shown in Fig. 4, is approximately twenty-seven inches x twenty-four inches, it is sufficiently large to be spread upon the leg or arm of a prospective buyer so that he may quickly and dependably form a definite conclusion of the appearance of clothing to be made from the fabric represented by the sample.

After each inspection of the sample is completed, the material may be neatly folded in the form shown in Fig. 6, and it is ready, without wrinkles, to be submitted to another prospective purchaser who, if he desires, may quickly release the fasteners and spread the fabric for a careful and minute examination.

It is apparent that I have invented a binder, and method of folding the sample fabric retained therein, which may be utilized for the purposes intended in a highly advantageous manner, it being apparent that the distance between the members of the fasteners may be varied in accordance with the size of the fabric sample and the width of the folds. Also, slots may be formed transversely of the inner side of the binder, if desirable, where the binder is formed from thick or stiff material.

If desirable, the fabric piece 22 may be cut to permit insertion of the fasteners whereby

the space 29, as shown in Fig. 7, between the ends of the fabric piece and the top 8 of the binder 1 may be eliminated.

It will now be apparent that I have devised a novel and useful binder and method of folding fabric samples, which embodies the features of advantages enumerated as desirable in the statement of the invention and the above description, and while I have, in the present instance, shown and described a preferred embodiment thereof and have specified dimensions of the binder and sample which will give in practice satisfactory and reliable results, it is to be understood that the same is susceptible of modification in various particulars and that binders and fabric of various sizes may be utilized for the intended purposes without departing from the spirit or scope of the invention or sacrificing any of its advantages.

What I claim as new and desire to secure by Letters Patent is:

1. The combination with a fabric sample folded end to end upon itself, of a binder receiving the ends of said sample and fixed thereto, and fasteners in said binder whereby when said binder and said sample are again folded the binder and the ends of said sample are releasably retained in folded position.

2. The combination with a fabric sample folded end to end upon itself, of a binder receiving the ends of said sample and fixed thereto, and fasteners in said binder whereby when said binder and said sample are again folded the binder and the ends of said sample are retained in folded position.

3. An article of manufacture comprising a fabric sample folded upon itself end to end, a binder secured to the ends of said sample, and said binder and said sample being folded with one end edge and one side edge, respectively, of said binder and said sample adjacent the inner portion of said binder and sample, and with the other end edge and side edge, respectively, of said binder and said sample being folded adjacent the edges of said binder and said sample formed by the last mentioned fold, and means to releasably retain said binder and the ends of said sample in the last mentioned folded position.

4. An article of manufacture comprising a fabric sample folded upon itself end to end, a binder secured to the ends of said sample, and said binder and said sample being folded with one end edge and one side edge, respectively, of said binder and said sample adjacent the inner portion of said binder and sample, and with the other end edge and side edge, respectively, of said binder and said sample being folded adjacent the edges of said binder and said sample formed by the last mentioned fold, and manually operative fasteners to releasably retain said binder and the ends of said sample in the last mentioned folded position.

5. An article of manufacture comprising a fabric sample, a binder secured to an end of said sample, and said binder and sample being folded with one end edge and one side edge, respectively, of said binder and said sample upon the inner portion of said binder and said sample, and with the other end edge and side edge, respectively, of said binder and said sample overlapping said last mentioned end edge and side, and means to releasably retain said binder and the end of said sample in the last mentioned folded position.

6. An article of manufacture comprising a fabric sample folded upon itself end to end, a binder secured to the ends of said sample, and said binder and sample being folded with one end edge and one side edge, respectively, of said binder and sample upon the inner portion of said binder and sample, and with the other end edge and said edge, respectively, of said binder and sample folded upon the last formed fold, and snaps in said binder to releasably retain said binder and the ends of said sample in the last mentioned folded position.
